UNITED STATES PATENT OFFICE.

DONALD PARKER, OF FRESNO, CALIFORNIA.

CONVEYER.

Application filed June 13, 1925. Serial No. 36,808.

To all whom it may concern:

Be it known that I, DONALD PARKER, a citizen of the United States, residing at Fresno, in the county of Fresno and State of California, have invented certain new and useful Improvements in Conveyers, of which the following is a specification.

In the present embodiment of gravity conveyers it has been found desirable to interrupt the gravity movement of articles thereon and during such time of interruption to separate the articles or space the ends of adjacent articles from each other. This is particularly true in packing house gravity conveyers wherein lug boxes filled with fruit move by gravity to certain points in the packing house. Under present conditions, it is extremely difficult when these filled boxes are contacting in end to end relation to remove a box from the line due to the difficulty in obtaining a hold on the end of the box, and also due to the end friction between adjacent boxes.

The present invention relates to a device or a conveyer structure whereby the movement or gravity travel of the boxes may be interrupted and during such time of interruption a number of the boxes on the conveyer may be separated from end contact with each other to enable the withdrawing of a box from the line.

The invention consists primarily in interposing in a conveyer a series of tilttable flat pivoted sections normally positioned with their upper surface in parallel relation with the remainder of the conveyer but adapted for pivotal movement to dispose the surface of their associated conveying members at an angle preferably in a direction reverse to the gravity flow of the boxes.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein:

Fig. 1 is a view in side elevation of one

embodiment of my invention as applied to a roller conveyer.

Fig. 2 is a view in top plan of the construction illustrated in Fig. 1.

Referring more particularly to the drawings wherein like characters of reference designate corresponding parts, the numerals

1 indicate the supporting legs of the conveyer side frame members 2 preferably arranged in parallel spaced relation and at a slight inclination toward one end to afford a gravity movement of receptacles to be conveyed. In the present illustration, a plurality of parallel spaced conveyer rollers 3 are disposed transversely between the frame members 2 and rotate as at 4 at their ends in the frame members 2. The rollers 3 in the present illustration are grouped at opposite ends of the frame members 2 affording a space substantially centrally of the frame members 2. In this space designated by the letter A are positioned a plurality of pairs of auxiliary frame members 5 fulcrumed substantially midway of their length as at 6 in opposing main frame members 2, and each pair carries a plurality of rotatable parallel spaced conveying rollers 7.

The rollers 7 are similar to the rollers 4 with the exception that they are grouped, and adjacent groups are carried by auxiliary frames independently pivoted within the space A between the main frame members 2. Depending from each of the auxiliary frame members 5 is a lever 8, the same being illustrated as pivotally connected at their lower ends to a connecting rod 9 which is in turn fulcrumed as at 10 to a pivotally mounted hand lever 11. The length of the auxiliary frames 5 approximates the length of the article, in this case a box, which the conveyer is designed to accommodate. In operation, filled boxes are delivered onto the upper end of the conveyer and roll by gravity toward the lower end being supported by the rollers 3 and 7.

An operator, desiring to remove a box from the line, or to interrupt the travel of the boxes downwardly of the conveyer, operates the handle 11 to tilt the auxiliary frames 5 to the dotted line position in the drawings. This movement interrupts the flow of boxes in rear of the auxiliary frames, causes the box overlying the auxiliary frames to separate at their adjacent ends enabling the operator to grasp the ends of the desired tilted box and remove the same from the line. Move-

ment of the lever 11 in an opposite direction will align rollers 7 with rollers 3 and permit the box to pass by gravity over the conveyer.

- 5 It will be observed that in the above described operation the boxes when tilted will be caused to move a slight distance backwardly on their respective rollers 7, and with the end wall contacting with the end 10 roller of a successive frame, and this pivoted movement, while but slight, causes a separation of the end walls of the box from each other and enables a ready grasping of the box end for removal from the conveyer.
- 15 It is to be understood that an entire conveyer may be constructed in this manner, and also that the auxiliary frames may only form a portion thereof, distributed throughout its length as efficiency requires.
- 20 It is also to be understood that while I have illustrated a plurality of auxiliary frames pivoted by one lever a separate lever may be provided for pivoting each frame, and it is to be understood that the fulcrum point 25 or spindle preferably the central roller 7 of the respective auxiliary frame members is illustrated to form the fulcrum mounting for the respective auxiliary frames, and that a separate fulcrum connection for the frame 30 may be provided if desired.

I claim:—

- 35 1. A conveyer consisting of a plurality of rotatable conveyer rollers normally disposed with their upper surfaces in substantially the same plane, and means for positioning groups of said conveyer rollers at similar inclinations with the corresponding rollers of adjacent groups in different parallel planes.
- 40 2. A conveyer consisting of a plurality of rotatable conveyer rollers normally disposed with their upper surfaces in substantially the same plane, and means for positioning groups of said conveyer rollers at similar 45 inclinations reverse to the direction of travel of articles on the conveyer, and with the corresponding rollers of adjacent groups in different parallel planes.

3. An inclined conveyer, longitudinally of which articles move by gravity during the 50 conveying thereof, and means for disposing a portion of the surface of successive adjacent portions of said conveyer at an incline reverse to the direction of travel of the articles on the conveyer with the adjacent 55 ends of adjacent portions in different horizontal planes.

4. A conveyer consisting of a main frame and a plurality of auxiliary frames disposed longitudinally thereof and pivotally mounted therein on an axis transversely disposed relative to the main frame, a plurality of conveying rollers rotatably carried by the auxiliary frames and constituting the supporting surface of the conveyer, and means 60 for tilting adjacent auxiliary frames endwise.

5. A conveyer consisting of a main frame, a plurality of rotatable conveying rollers disposed transversely thereof for a portion 70 of its length, a plurality of auxiliary frames fulcrumed within said main frame on an axis transversely thereof, a plurality of rollers carried by the auxiliary frames and disposed transversely of the main frame, 75 said main and auxiliary frame rollers constituting the conveying bed, arms extending from said auxiliary frames, means connecting said arms and an operating device for said means whereby adjacent auxiliary 80 frames are simultaneously inclined endwise within said main frame.

6. In combination with a conveyer longitudinally of which a plurality of articles are adapted for movement by gravity with 85 their ends in contact, of means within the length of said conveyer for operation to dispose the articles at an incline to the horizontal to arrest the movement of the said articles thereon with their ends spaced from 90 the corresponding ends of the adjacent arrested articles.

In testimony whereof I have signed my name to this specification.

DONALD PARKER.
